UNITED STATES PATENT OFFICE.

EUGENE G. SMITH, OF CHICAGO, ILLINOIS.

AXLE TRANSMISSION FOR RAILWAY-CARS.

1,379,055.

Specification of Letters Patent. Patented May 24, 1921.

Application filed December 31, 1920. Serial No. 434,201.

To all whom it may concern:

Be it known that I, EUGENE G. SMITH, a citizen of the United States of America, residing at Chicago, in the county of Cook and State of Illinois, have invented certain new and useful Improvements in Axle Transmission for Railway-Cars, of which the following is a specification.

My invention relates to improvements in axle transmission for railway cars to generate electricity, or otherwise, and the principal objects of my improvement are,

First, to provide a power transmission wheel preferably of the pulley type, or otherwise, adapted to meet a great number of conditions as to flexibility between the driving and driven members, particularly for use in axle-generation of electricity for railway car lighting, or otherwise;

Second, the provision of improved means adopted to be operatively mounted on any size car axle;

Third, to produce a construction whereby to lubricate the wear parts through spokes that are hollow and serve to carry and distribute lubricating substance;

Fourth, the production of a structure of few parts and a wide range of utility; and,

Fifth, to afford a practical construction capable of being installed and demounted in a comparatively short period of time.

With the above and other related objects in view, my invention consists in the novel features and in the novel combination and arrangement of parts hereinafter fully described, illustrated in the accompanying drawings forming a part of this specification, and particularly pointed out in the claims hereunto appended; it being understood that changes, variations and modifications in the details of the invention within the scope of the claims, may be resorted to without departing from or sacrificing any of the advantages thereof.

In the drawings,

Figure 1, is side elevation of my improvement, assembled and applied to a railway car,

Fig. 2, is a central sectional view of a demountable drive-wheel of the pulley-type and hub-means for attaching and detaching said drive-wheel to and from the railway axle,

Fig. 3 is a cross section of the drive-wheel on line 3—3 in Fig. 2, with parts in elevation

and with flexibility illustrated by dotted lines,

Fig. 4 is a perspective of a fixed member of a half of the hub, there being two of such members,

Fig. 5 is a similar view of a movable clamp member of said hub, there being two of such clamp members.

Similar numerals and letters refer to like parts throughout the several views.

In the embodiment to exemplify my invention, I employ a flexible wheel preferably of the pulley type, but I do not intend to limit my invention to the use of a pulley type of drive-wheel, as the fellies of the wheel may be made to carry for example, a spur gear meshing with an elongated pinion, thus making it a positive drive instead of a belt drive, by omitting the belt-tightening device, changes which would occur to mechanics skilled in this art.

For a more detailed description, 6 designates the body of a railway car, 7 denotes an electric generator which is fixed to the car in any desired manner, 8 indicates a pulley wheel which is fixed to the armature shaft 9 of the generator 7.

The belt-tightening device may be of any preferred construction as herein the arm 10 is pivoted at 11 to the generator supporting frame 12, and carried flanged wheel 13, which is in operative connection with the flexible drive-wheel 14, by belt 15, all hereinafter more fully described. The shafting 16 carried a compression spring 17, which constantly urges the arm 10 and its flanged wheel 13 against the belt 15 sufficiently to take up any slack that from any cause arises.

Only one car wheel 18, of one of the railway trucks is shown. In practice, the axle nearest the center of the car is used to which to attach the flexible drive-wheel for generating purposes.

The detachable flexible drive-wheel 14, 100 preferably is composed of a link comprising two fixed members 19, 20, just alike, a description of one is a description of both, and two movable clamp members, 21 and 22, both alike. The fixed members, 19, 20, are riveted together at 23, 24, through lugs 25, 26, and are formed externally with bosses 27, which are threaded to receive long machine screws 28, and provided with lock nuts 29. Each part 19, 20, is formed with a half bear-

ing 30, 31. Each part 21, 22, is formed with longitudinal corrugations, 32 on its concave surface and on its convex surface with trunnion 33. Each part 19, 20, is recessed 5 at 34 to receive one of said trunnions 33.

Said flexible driving member 14 preferably is provided with a plurality of fellies 35, which are fixed together at their contiguous ends by felly-plates 36, by rivets 37.

10 Each felly-plate 36, is formed with a boss 38, having a journal bearing 39, opening inwardly. Each felly, and each felly-plate is formed with a path of travel for the belt 15.

15 Because of the lack of uniformity in the diameters of the different railway car axles A, I have provided the movable parts 21, 22, and their environment.

In order to provide sufficient flexibility of 20 the drive-wheel 14, I have produced the structure herein which requires means for some rotation of each spoke at both ends and corresponding journal bearings, with simple means for lubrication of the wearing parts. Therefore, preferably, I employ a 25 plurality of spokes 40, preferably hollow, but not limited thereto. The spokes 40 are alike and the description of one spoke is a description of all spokes in the structure. 30 Each end of each spoke is provided with a plug 41, a bushing 42, a longitudinal oil aperture 43, oil exits 44, and pin 45, and intermediate ends of each spoke 40, there is a threaded plug 46 for oil or grease intake. 35 Preferably there is used a quantity of absorbent material 47.

The drive-wheel 14 is provided with external annular flanges 48, 49, between which the belt 15 travels.

40 The construction and operation of my invention is thought to be so simple that on reference to the drawings taken in connection with the foregoing description, those skilled in this art will readily be able to 45 make and operate my invention.

By thus showing and specifically describing the embodiment herein of my invention, I do not intend to restrict the range of equivalents more than is made necessary by 50 the prior state of this art.

Having thus fully described my invention, what I claim as new and desire to secure by Letters-Patent, is—

1. In mechanism of the class described, 55 the combination with a railway car axle, of a driving wheel having a hub, means to rigidly secure said hub to said axle, a plurality of fellies, felly-plates formed with bearings fixed to the contiguous ends of said

fellies, the peripheries of said fellies being 60 formed with an external annular recess, and a plurality of hollow spokes journaled at their inner ends in said hub and at their outer ends in the bearings of said felly-plates. 65

2. In mechanism of the class described, the combination with a car axle, of a driving wheel having a hub, means to rigidly secure said hub to said axle, a plurality of fellies, felly-plates formed with bearings 70 fixed to the contiguous ends of said fellies, the periphery of said fellies being formed with belt-retaining external annular flanges, and a plurality of spokes journaled at their inner ends in said hub and at their outer 75 ends in the bearings carried by said felly-plates, said spokes being formed to afford means to carry lubricant for ends of said spokes.

3. In mechanism of the class described, 80 the combination with a car axle, a generator and power transmission connection between the axle and the generator, of a drive-wheel having a demountable hub, means to fix the hub to the axle, and spokes of said drive-wheel being capable of some rotation 85 at both ends thereof.

4. In mechanism of the class described, a drive-wheel having a demountable hub, and a plurality of hollow spokes adapted 90 for rotation relative to the hub.

5. In mechanism of the class described, the combination with a driven member and a driving member in power transmission relation to each other the driving member 95 including a car axle, a demountable hub rigidly fixed to the axle, a plurality of fellies, felly-plates formed with journal bearings fixed to the contiguous ends of the fellies, and a plurality of spokes journaled at their inner ends in said hub, and at their outer 100 ends in the bearings carried by said felly-plates.

6. In mechanism of the class described, the combination with a driven member and a driving member in power transmission relation to each other, the driving member including a car axle, a demountable hub rigidly fixed to the axle, a plurality of fellies, felly-plates formed with journal bearings 110 fixed to the contiguous ends of the fellies, and a plurality of spokes journaled at their inner ends in said hub, and journaled at their outer ends in the bearings carried by said felly-plates, and a belt-tightening device. 115

In testimony whereof I affix my signature.
EUGENE G. SMITH.
